ABSTRACT

A hydraulic control apparatus comprising a plurality of standard multiple function conduit modules adapted to be selectively programmed in various arrays to effect substantially any required hydraulic control functions. The apparatus is further characterized by universal multiple function valve modules which co-operate with the conduit modules in effecting the control functions.

INTEGRATED MANIFOLD CIRCUITS

This is a continuation of my co-ending application, Ser. No. 852,231, filed Aug. 22, 1969 now U.S. Pat. No. 3,589,387.

This invention relates generally to hydraulic apparatus and more particularly to fluid power control systems adapted to be fabricated from a plurality of multiple function standardized components.

In the fabrication of hydraulic control systems, such as power packages for the industrial field as well as for pump, motor and control valve assemblies for mobile equipment, military applications, and other uses where controlled fluid power systems are required, it has been the practice in the art to fabricate the control systems from various control valves and associated components that are connected in circuit by external piping.

In other instances, it is a practice in the art to join together such valves and components in contiguous relationship so as to eliminate some external piping by bolting together housings of individual components such that the ports in one housing connect directly with the ports of the next adjacent housings of the system. This approach has resulted in the elimination of certain external piping but the applications have been specialized and have consisted of custom built housings and bases constructed for the particular application without any provision for standardization and interchangeability of multiple function modular components. Such conventional hydraulic control systems which inherently require a plurality of individual control valves for performing different control functions have traditionally associated together various valves of both standard and specially designed construction, with the result that each of the individual control valves has been incorporated in the overall control system as a separate species constructed of its own respective specialized valve components.

In accordance with the present invention, a unique system is provided for fabricating substantially any fluid power control system to perform substantially any control function, both simple and sophisticated, from a plurality of multiple function standardized circuit-forming block components of modules without the use of major interconnecting piping conduits.

As another aspect of the present invention, the circuit-forming modules are all uniquely arranged to include what will be termed herein a "dual duct - 4 port" configuration which can be arranged and programmed with standardization to selectively provide series, parallel and series-parallel hydraulic circuitry applications.

As another aspect of the present invention, the novel system incorporates multiple function basic control valve modules of standardized construction, including a multiple function spool valve element, which can be applied to the above mentioned system in a variety of selectively programmed modulating and switching configurations so as to provide a variety of control functions, as well as a variety of structural arrays such that virtually any simple or complex hydraulic control applications can be achieved from standardized multiple function valving modules.

As another object of the present invention, the above mentioned standardized multiple function valve modules are adapted to co-operate in a unique way with the above mentioned multiple function valving module so as to permit the fabrication of substantially any com-

posite hydraulic control system from a relatively small inventory of standardized multiple purpose blocks or modules of simple, inexpensive design.

As another aspect of the present invention, the standardized components include the unique combination of a standardized center block module adapted to register and co-operate with parallel side block modules in an infinite variety of arrays with said center block module providing the multiple function of a mounting means for the selected valving module and also the junction for a plurality of outwardly extending side arm assemblies of the above mentioned standardized conduit modules. It will be understood that with this arrangement, various different control and circuit-forming functions can be respectively provided by the outwardly extending side arm assemblies with the switching of flow between the side arm assemblies being affected by the above mentioned center block and associated valve module so as to accomplish any selected interbranch valving function. Moreover, and most important, any or all of the above mentioned side arm assemblies can in turn be arranged to communicate with additional center blocks and thereby deliver a switched or controlled flow to a next successive valving module on the additional center block so as to vary, amplify or refine the flow. It will now be understood that various control flows can be divided, combined, modulated, amplified and treated in various ways merely by the use of the standardized circuit-forming modules and valve modules defined above.

As still another aspect of the present invention, all of the above mentioned center block, side block and bus block modules, as well as spacer block modules adapted for use therewith, are structurally standardized to the extent that their ultimate three-dimensional assembly into an array of standard valve controlled branches can be accurately, schematically depicted on a two-dimensional schematic drawing or flow strip such that even the more complex flow paths as well as the valving functions performed thereon can be easily designed and readily understood. This permits a hydraulic technician with ordinary skill to readily program a selected control system on a two-dimension flow diagram in a manner that he can readily select the necessary standard valve modules required for the particular application. It should be emphasized that it is only by the overall standardization of all of the various components described above that such simplification of a three-dimensional apparatus to a two-dimensional flow strip can be realized.

Further objects and advantages of the present invention will be apparent from the following description, reference being had to the accompanying drawings wherein a preferred form of embodiment of the invention is clearly shown.

In the drawings:

FIG. 1 illustrates a typical fluid power control system, constructed in accordance with the present invention;

FIG. 2 is a diagrammatic view showing the flow circuit of the hydraulic control apparatus of FIG. 1;

FIG. 3 represents a flow strip display of the schematic flow circuit represented in the hydraulic control system of FIG. 2. This flow circuit of FIG. 3 is functionally the same as that shown in FIG. 2, but has been transposed into the flow strip from so as to show a dual duct passage arrangement of the various modules and components of FIG. 1. Such modules and components of FIG.

1 are each illustrated by dotted delineation in FIG. 3;

FIG. 4 illustrates the total assembly of conduit modules that provide the dual duct flow paths in the typical hydraulic control system of FIG. 1. Here the valve modules, control modules and fastening rods have been removed;

FIG. 5 is a partial exploded view of a first assembly comprising a portion of the control system of FIG. 1;

FIG. 6 is an exploded view illustrating a second branch assembly comprising another portion of the control system of FIG. 1;

FIG. 7 is an exploded view illustrating a bus assembly comprising another portion of the control system of FIG. 1;

FIG. 8 is a sectional view of a safety relief valve version of an universal power flow valve module of the present invention with the section being taken along line 8—8 of FIG. 13;

FIGS. 9—12 are elevational views of the safety relief valve of FIG. 8;

FIG. 13 is another sectional view of the safety relief valve of FIGS. 8—12, with the section being taken along line 13—13 of FIG. 9;

FIG. 14 is a partial sectional view showing a spool spacer option for modifying the power flow valve module of FIGS. 8—13;

FIG. 15 is a partial sectional view corresponding to FIG. 14 but showing the assembly with the spool spacer removed;

FIGS. 16—19 are elevational views of a direct spring bias cross relief valve comprising a version of the valve module of the system of the present invention;

FIG. 20 is a sectional view showing the interior construction of the cross relief valve module of FIGS. 16—19, the section being taken along the line 20—20 of FIG. 16;

FIGS. 21—24 are elevational views of a pressure compensated flow control valve comprising another version of the power flow valve module of the system of the present invention;

FIG. 25 is a sectional view showing the interior of the pressure compensated flow control valve of FIGS. 21—24, the section being taken along the line 25—25 of FIG. 21;

FIGS. 26 and 27 are sectional views of a check valve plate module used in connection with certain of the valve modules of the preceding figures;

FIG. 28 is a diagrammatic view of the circuit for the safety relief valve of FIGS. 8—14;

FIG. 28-A is a legend showing line plug and orifice symbols used in various diagrammatic views of valving circuits of the present drawings;

FIG. 29 is a diagrammatic view of a typical four-way directional valve utilized in the typical system of FIG. 1;

FIG. 30 is a diagrammatic view showing the control program arrangement of a counter-balance valve module of the typical system of FIG. 1;

FIG. 31 is a diagrammatic view showing the control program arrangement of the pressure compensated flow control valve module of FIGS. 21—25;

FIG. 32 is a diagrammatic view showing the control program arrangement of the cross relief valve module of FIGS. 16—20;

FIG. 33 is a diagrammatic view of the four-way valve comprising a portion of the system of FIG. 1; and

FIG. 34 is a diagrammatic view of a return line filter

module comprising a portion of the system of FIG. 1.

Referring in detail to the drawings, a typical fluid power control system is indicated generally at 20 in FIG. 1 and is constructed from conduit and valve modules provided with common interface characteristics, such as seals, rods, ports, between the conduit modules. These blocks are divided into important functional categories later to be described in detail herein. In general, the blocks are arranged in a typical bus assembly 42, FIGS. 1, 3 and 7, which provides dual duct conduits for the pressure and flow from a centralized source of pressurized fluid such as a variable volume pump 66 illustrated in FIG. 2 as well as for flow back to a reservoir 74. Such dual duct arrangement consists of a pressurized duct 110 which is connected to pump 66 and a drain duct 112 is connected to reservoir 74.

It will now be seen that bus assembly 42 and the ducts 110 and 112 provide pressure and drain for two branch assemblies of dual duct conduit modules, a first branch 20 being indicated generally at 130 and the second branch being indicated generally at 132. Each of the branches coming from the bus ducts 110 and 112 represents a complete manifold assembly for operating specific fluid motor functions. For branch 130, a typical rotary type motor load is indicated at 108, FIG. 2, and for branch 132 the power cylinder 106 of FIG. 2 represents a typical load.

First branch 130 is mounted on bus assembly 42 by a bus adapter block 34 directly connected to a center block 30. A parallel side block 26 is mounted on the top face of center block 30 and in turn serves to mount a second parallel side block 22. The entire branch assembly 130 is fastened to bus block 36 of bus assembly 42 by mounting bolts 146 extended through holes 151 in base flanges on bus adapter block 34 and into threaded holes 153 in the top surface of bus block 36.

It should be mentioned that interface seals for the dual duct functions between the branch and bus modules are provided by a standard T-seal construction seen at 120 in FIG. 5. The duct 134 and 136 of first branch 130, in FIG. 1, lead to the fluid motor 108 as seen in FIGS. 2 and 3. Here will be seen the outlet ports for such ducts 134 and 136 are in the top interface of parallel side block 22 as seen at 134-A and 136-A.

Reference is next made to second branch assembly 132, FIGS. 1—4 and 6, mounted on bus assembly 42 by a bus adapter block 78. A center block 80 has its lower face mounted on bus adapter block 78 and the upper face of the center block supports a one-third spacer block 96 and parallel side block 98 as is best seen in FIG. 6. Also, a side fact 149 of center block 80 mounts two one-third spacer blocks 84 and 86 as well as a parallel side block 88.

The entire branch assemblies 130 and 132 are each mounted on bus assembly 42 by bolts 146 that extend through holes 151 through base flanges on bus adapter blocks 34 and 78.

Referring again to FIGS. 1—4, power cylinder 106 is connected to duct 140 at outlet port 140-A. Conduits 138 and 142 are provided with plugs 91 and 93 in the final assembly since these conduit ports are not utilized in the particular typical control system.

Referring particularly to FIGS. 1, 4 and 7, bus assembly 42 comprises standard modules comprising bus block 36, parallel side block 44, full standard spacers 50 and 52, bus block 54, full standard spacer 56 and series side block 58, all bolted together by standard mani-

fold rods 122 of the required length. Also manifold rods are used for securing together the modules of the branches as seen at 114. The bus rods 122 extend through all of the bus modules and are secured at each end by rod nuts 118. Hence it will be seen that the standard rods provide means for connecting together any selected branch or bus assembly of conduit modules and performs the compression on the interface between the conduit modules and seals 120 for the standard dual duct system. The interface seal construction 120 is also illustrated in FIG. 5, an exploded view of branch 130, and these seals are provided at each interface junction between conduit blocks.

FIG. 7 illustrates an exploded perspective view of bus assembly 42 which also utilizes the standard seals 120 at the abutting interfaces of the bus modules.

The rods 122 that are used to assemble the bus modules are of the same diameter and include the same thread characteristics as the rods 114 that are used to mount the various modules to the center blocks 30 and 80 in the branch assemblies 130 and 132, the only difference being that the rods 114 that mount to the center blocks actually thread into tapped holes 155 in the center blocks and secure the side blocks and other modules to the center blocks, whereas the rods 122 that mount the bus modules together extend through the entire bus assembly and their threaded ends are provided with standard manifold rod nuts 118. Also, fastening rods 114 and 122 are provided with flats, not illustrated, adjacent their threaded ends, to permit gripping the rods with a wrench when the rods are screwed into female threaded members and tightened.

It should further be pointed out that the relative lengths of the conduit modules in the direction of the dual ducts, such as ducts 110 and 112, are as follows, assuming a standard arbitrary module length X:

Module	Relative Length
1. Bus Block 36-54	2X
2. Bus Adapter 34-78	1X
3. Parallel Side Block P1-P2, 22-36-44-88	1X
4. Parallel Side Block P1-P3, 98	1X
5. Parallel Side Block P2-P3	1X
6. Parallel Side Block P1-P2-P3	1X
7. One-Third Standard Spacer (Through) 86	½X
8. One-Third Standard Spacer (1 Duct Blocked) 84	½X
9. Full Standard Spacer, 50-52-56	1X
10. Series Side Block 58	2X
11. Center Block 80-30 — Terminal Block for Rod Ends	(any appropriate length)

The standard fastening rods length 114 and 122 and the module lengths represented by X and whole and fractional multiples of X in the above table are all established to be multiples of a standard arbitrary module length whereby a relatively few standard rods can be selectively used to secure together various selected combinations of modules.

It will now be understood that the dual duct arrangement which is of a specific diameter and specific space orientation throughout the entire conduit block apparatus, is maintained constant throughout the system. For instance, the conduit spacing, size and seal arrangement in the branch assemblies 130 and 132 are exactly the same as the corresponding characteristics in the bus assembly.

All blocks mounted to center blocks, such as center blocks 30 and 80 in FIG. 1, are identical in their interface characteristics with the result that any block which is positioned at any location in the entire system can be

selectively mounted at any other location in the control system for interchangeability and universally common characteristics.

In general, another important novel feature of the standard dual duct principle is that the dual ducts in the branch assemblies, such as 130 and 132, are adapted for the mounting of standard power flow valve modules, which are mounted on standard center block modules 30 and 80. This arrangement permits diverting or switching flow from the main dual ducts to any required porting in the sides of the center blocks. Such side porting and the valve passages in turn function as dual duct conduits and hence directional flow control is performed by a center block and valve combination such that the flow from a center block module to other modules in the branch assembly is determined by the switching characteristics of the particular directional valve mounted on the center block. When the flow is switched to the side faces of the center block, it is always returned to the dual duct passages of the conduit modules with the flexibility of being able to program various types of modulating and flow switching valves to effect whatever flow or directional characteristics are required for the particular control system.

Reference is next made to FIG. 3 which is a flow strip diagram, depicted in two dimension, single plane arrangement for simplicity of analysis of the three-dimensional array that forms the control system of FIG. 1. Here it is easy to trace the flow of fluid from the pressure source, hydraulic pump 66, through the entire integrated manifold assembly which delivers controlled flow to the typical loads provided by rotary fluid motor 108 and power cylinder 106. A pressurized bus duct 110 connects pump 66 to an inlet port 110-A to the hydraulic control apparatus 20 and a low pressure bus duct 112 returns flow to reservoir 74 via outlet port 112-A of the control apparatus. Hence the flow proceeds through bus block assembly 42 in a standard dual duct arrangement that services the two branch assemblies 130 and 132 previously described.

As seen in FIG. 3, the flow entering pressurized bus duct 110 via inlet port 110-A proceeds through a series side block module 58, full standard spacer 56, and then to a first bus block 54. At that point, pressurized flow is diverted to pressurized branch duct 138 by a bus adapter block 78 to a center block 80 of branch assembly 132. At center block 80 the flow is switched by a four-way directional valve 82 which is illustrated mounted on a face of center block 80. In operation, the flow is switched from an internal pressurized passage 150 of four-way directional valve 82 to an outlet passage 152 and proceeds through branch duct 138 of one-third standard spacer module 96 located in a side arm circuit of branch 132. The flow from one-third standard spacer module 96 proceeds into a parallel side block 98 which mounts a pressure compensated flow control valve module 100 and a reverse check plate module 120. The flow then proceeds by series type through valve module 100 into branch duct 140 and port 140-A leading to power cylinder 106. With this type of flow through pressure compensated flow control valve 100 to duct 140, it will be seen that the flow is blocked by an obstruction 158 in duct 140 located in one of the duct forming portions of one-third standard spacer 96.

It will now be seen that the original dual duct flow in branch 132 is converted to single duct flow to power

cylinder 106 by obstruction 158. As the pressurized flow is directed into the rod end of power cylinder 106 via duct 140, discharge flow from the other end of power cylinder 106 is delivered via port 144-A and returned to a side arm assembly on center block 80 which side arm includes one-third standard spacers 84 and 86 and parallel side block 88, FIGS. 1, 3 and 4.

Side block 88 mounts a standard power flow valve module programmed as a counter-balance valve 90, which maintains back pressure on power cylinder 106 responsive to a control adjuster 92 and a check valve 94 which provides a blocked flow condition in the direction from power cylinder 106 back to center block 80. The flow from line 144 and side arm duct 161, FIG. 3, passes through counter-balance valve 90 to the other side arm duct 142. At this point it should be pointed out that there is an obstruction 160 to duct 144, said obstruction being located in one-third spacer 84. This prevents return flow from line 144 from being delivered back to the center block via passage 156. Return flow must therefore proceed through passage 142 back to the passage 154 of four-way valve 82 at center block 80. It should be mentioned that when four-way valve 82 was switched so that passage 150 was connected to 152, passage 154 is also connected to passage 156 by the same action of the four-way valve. Therefore the return flow proceeds from passage 154 to passage 156 and branch duct 140 leading to low pressure bus duct 112. At this point the return flow is directed through a return line filter 62 or a return line bypass relief valve 64 and then via line 112 to reservoir 74. Here an obstruction 166 in series side block 58 prevents a short circuit flow to reservoir around the filter 62 and bypass relief valve 64.

With continued reference to the flow arrangement for branch assembly 132, FIGS. 2 and 3, it will be understood that if pressure delivered to line 150 of four-way valve 82 had been diverted to output passage 154, and passage 152 of said valve 82 had been connected to passage 156 by the action of four-way valve 82, then the reverse flow to power cylinder 106 is delivered via passage 142 and check valve 94 in counter-balance valve 88 in a dual duct arrangement, and power cylinder 106 is thereby operated in reverse such that the discharge flow returns through branch duct 140 in parallel side block 198 to pressure compensated flow control valve 100 and the reverse check valve module 102 to branch duct 133 and leading to passage 154 of four-way valve 82. The valve connects passage 152 to passage 156 and flow passes via ducts 140 and 112 to return the line filter 62 and bypass relief 64 in series side block 58 and back to reservoir 74.

In summary, the entire branch assembly 132 provides a control function in which four-way valve 82, mounted on center block 80, performs a switching function for the pressure and return flows from bus assembly 42 to power cylinder 106 accomplishing pressure and flow control of such cylinder and its load, in a precise and definite manner through the entire conduit module assembly of branch 132.

With continued reference to FIG. 3, the flow to and through first branch assembly 130 will next be described. The same pressurized bus duct 110 that supplies the branch 132, just described, flows through full standard spacer modules 52 and 50 and parallel side block 44 to bus block 36. Parallel flow is normally maintained in the two bus ducts 110 and 112 of parallel

side block 144. However, a safety relief valve 46 is mounted on parallel side block 44, FIG. 1, such that if for some reason the pressure in pressurized bus duct 110 increases above the pre-selected spring setting of pressure relief valve 46 then flow occurs from pressurized bus duct 110 to bus return line 112 thereby releasing pressure to reservoir. In normal operation, however, the fluid with rising pressure is delivered to branch assembly 130 via bus adapter block 34 and then to a second center block 30 on which is mounted a four-way directional control valve 32 provided for the switching of pressurized fluid between opposite sides of a typical load in the form of a rotary fluid motor 108 and the control circuit therefor. More specifically, when the motor is driven in the forward direction of rotation pressurized fluid in passage 172 is delivered to passage 174 of four-way directional valve 32 while return flow from motor 108 is delivered from passage 176 to passage 178 which communicates with branch duct 136 and the latter communicates with bus drain duct 112 leading back to reservoir 74.

With continued reference to FIGS. 2 and 3, pressurized flow from valve passage 172 to 174 proceeds up the motor branch duct 134 via port 134-A to fluid motor 108 to drive the fluid motor in the forward direction or rotation. Discharge flow from fluid motor 108 is then received via port 136-A at branch duct 136 and returned to valve passages 176 and 178 and thence through the branch duct 136 and bus duct 112 to reservoir. During certain operational conditions of fluid motor 108, such as stopping or stalling of the motor, pressure in line 134 will rise to a higher value and the cross relief valve 28 mounted on parallel side block 26 relieves the pressure from branch duct 134 to branch duct 136 to bypass fluid motor 108 responsive to the adjustment of adjuster 40 of a cross relief valve 28. Similarly during reverse operation of the motor cross relief valve 24 mounted on upper parallel side block 22 releases pressurized fluid from branch duct 136 to branch duct 134 during operating conditions when the pressure rise in line 36 exceeded the preselected adjustment setting of adjuster 38 of cross relief valve 24.

It will now be seen that the cross relief valves perform pressure control functions in parallel relationship with fluid motor 108 across side arm ducts 136 and 134.

Referring again to FIG. 3, duct obstructions 170 and 168 are provided in center block 30 to block flow in the dual duct passages which are prevented from being short circuited around four-way valve 32 by such blocked passage in center block module 30.

Similarly, in the branch assembly 132, previously described, the bus obstruction 162 and 164 in center block 80 prevent short circuit around four-way valve 82.

A description of the details of the various modules are set forth in detail in my-copending application, Ser. No. 852,231 filed Aug. 22, 1969.

It should be mentioned that in FIGS. 4, 5 and 6 the showing of valve mounting interface 255 of center block module 80-30 omits certain of the minor passages and dowel locating holes.

It should also be mentioned generally that the standard interface ports 15, in all the conduit modules, are offset from center with respect to the rod mounting 16 such that protruding standard T-seals 120 function as locating "pins" as well as seals. This prevents the possibility of upside-down assembly of the various modules.

At the same time the modules can be selectively assembled such that the main dual ducts, such as 110 and 112 or 134 and 136 can be joined in normal assembly, termed herein as "polarized" assembly, or they can be assembled to reverse the main ducts to provide what will be termed "reverse polarization." For example, the parallel side blocks 22 and 26 in branch assembly 130, FIGS. 1 - 7, are assembled such that module 26 is installed with respect to module 22 and center block 30 so as to provide reverse polarization to accomplish the cross relief valving function later to be described herein.

With continued reference to the polarization and reverse polarization assembly, the flow strip diagram of FIG. 3 shows an arbitrary "starting reference point" at the bus block module 54. At this point normal polarity occurs in the main bus ducts 110 and 112. At other modules in the system where the above mentioned reverse polarity occurs this is indicated by an "R" on the flow strip diagram of FIG. 3.

Each standard conduit module is provided with arrows 291, some of which are shown located on one side of the module adjacent to the flow path interfaces. Normal assembly (polarized) of modules occurs with all arrows at the same side of each module. Reverse assembly of a module (reverse polarization) is specified with arrows on opposite side of assembly. "Polarized assembly" begins with arrows on the "Starting Module" such as a "Center block" or a "bus block," etc., acting as the reference positions. (Reverse Polarization is indicated in an IMC Flow Strip station by an (R) in the upper center of the station.)

Reference is next made to safety relief valve module 46 shown mounted in the control apparatus in FIG. 1 and illustrated in detail in FIGS. 8 - 13 and schematically in FIG. 28. Module 46 is a typical universal valve module programmed to function as a safety relief valve between the pressure and drain ducts 110 and 112 of bus assembly 42. FIG. 3 shows such safety relief valve 46 as being located in parallel across main bus ducts of the bus assembly 42.

With reference to FIG. 28, pressurized duct 110 in bus assembly 42 communicates with inlet port 244 of safety relief valve 46 and drain duct 112 of the bus assembly communicates with line 238 of safety relief valve 46.

It should be pointed out that safety relief valve 46, FIG. 28, represents a programmed assembly of an universal power flow valve module indicated generally at 222 and an universal signal flow valve module indicated generally at 228.

It should also be mentioned that the schematic illustration of power flow module 222, in FIG. 28, illustrates the selected programming of various spool springs, orifices, etc., incorporated in the universal power flow module of the present invention.

Referring next to the sectional view of FIG. 13, structurally the module 222 includes a housing 180 in which is mounted a valve sleeve 182 which contains a power spool 184. This spool and associated valve elements in combination represent the universal power flow valve module that can be programmed to provide all types of flow switching and modulating functions in fluid power control systems. The valve spool 184 is actuated in sleeve 182 by the action of control spring 194 acting on a control spring adapter 196 which is slideably mounted on a spool extension 198 and confined in the

assembly by the abutment 197 on the sleeve in one direction, and by a shoulder 201 on spring housing 192 in the opposite direction. Control spring 194, FIG. 13, urges spool 184 inwardly in sleeve 182 until control spring adapter 196 engages the upper end of the sleeve. Referring to the opposite end of the spool, a reset spring adapter 226 engages the left end 295 of spool 184 and is in force transmitting relationship with the spool. Spring 230 acts on reset spring adapter 226 and biases the spool into contact with the spring and spacer arrangement on the opposite end. Spring 230 reacts against the housing via a spring retaining plug 232 and the spool 184 is thereby held at a normally closed position all ports, relative to sleeve 182 as shown in FIG. 13.

It should be mentioned that control spring adapter 196 slideably receives spool extension 198 such that upon application of fluid pressure in chamber 348, spool 184 can shift to the left against the force of the opposite reset spring 230 with spool extension 198 functioning as a spring adapter guide. Spring 194 and spring adapter 196 do not move to the left but remain stationary in their position of FIG. 13 as spool 184 moves to the left and remains guided and centered by spool extension 198. This arrangement permits spool 184 to be shifted to the left of its normal position only by the hydraulic pressure and not by mechanical action of spring 194.

Conversely, if hydraulic pressure is applied to the opposite left end 295 of spool 184 via chamber 346 and orifices 234 in spring adapter 226, control spring 194 and spring adapter 196 are compressed to the right until spring adapter 196 is stopped by a shoulder 201 on spring housing 192.

It will now be understood that spool 184 is shiftably mounted between two springs with control spring 194 being of greater force magnitude than reset spring 230, thereby establishing the normal centered position of spool 184 within its sleeve 182. However, hydraulic pressure applied to either end of spool 184 will move the spool in a respective direction against the opposite spring and when hydraulic pressure is removed from the spool ends the spool will return to its original spring center normal position.

Referring particularly to FIGS. 13 and 28, the signal flow valve elements for safety relief valve 46 are mounted in a signal flow valve module section 228 and include a signal spool 276 mounted in a sleeve 278 which in turn is mounted in a housing 203. The spool and sleeve arrangement is secured in the housing by a spring housing 280, FIG. 13, which engages sleeve 278 at an end surface 205 to form a completed assembly. Signal spool 276 is provided with an end adapter 207 which in turn engages a ball 272 mounted in a spring retainer 270. The upper end of a signal flow control spring 266 engages a second retainer 268 which in turn engages a ball 264 which is biased by stem 260. Such stem is provided with threads 209 for longitudinal movement within its housing. The stem 260 is provided with an adjustment knob 256 which is secured in place by set screw 258 and a friction lock nut 262.

Signal spool 276 includes a left end 352 exposed to fluid in chamber 350, and as pressure is increased in this chamber the action opposes the forces generated by signal flow control spring 266 on the right of the spool. As pressure rises beyond the setting of the spring 266, the spool is shifted to the right to connect certain

ports, later to be described, for delivering control pressures resulting from signal flow arrangements to power flow spool 183, previously described.

Referring again to FIG. 28, the schematic of the safety relief valve 46, this diagram represents a combination multiple function valve module which can be programmed in many ways to accomplish a wide variety of flow control possibilities with the signal and power spool elements. The orifices and passage options are programmable by either installing or removing orifice elements and plugs from passages of an universal passage arrangement. The legend for the application of plugs and orifices to the various schematic diagrams of the present application is shown in FIG. 28-A.

Referring again to FIG. 28, the particular programming of the modules for safety relief valve 46 and the specific arrangement of control orifices and flow paths are shown using the symbols of FIG. 28-A. Flow enters port 244 via bus duct 110 and it is directed via line 368 to recess port 218 of the sleeve and spool arrangement and pressurizes annular spool passage 216 and is also reflected to end 295 of power spool 184 via passage 376, passage opening 320 and check valve 226 biased by reset spring 230.

Pressurized fluid is also directed to chamber 348 at the opposite end of power spool 184 via recess 218, lines 382 and 380, orifices 382, 302 and 308, and sleeve recess 372. The spool is therefore exposed to static pressures on each end as long as certain control flow situations do not occur, as will later be described, and the spool remains in its normally closed position as determined by control spring 194.

With continued reference to FIG. 28, pressurized fluid is also conveyed via orifice 318 and passage 296 to the end 352 of signal spool 276 at chamber 350. The opposite end of signal spool 276 is controlled via recess 364, passage 252, including opening 312, opening 324 in passage 252, valve outlet port 238 and bus drain duct 112 leading to reservoir 74.

As seen in FIG. 28, spring 266 biases signal spool 276 against the hydraulic pressure acting on the spool end 352. Action of such pressure on spool end 352 will move the signal spool against spring 266 to open certain ports and thereby develop signal flow for pilot operation of the power flow spool 184 in module 222, later to be described.

Referring again to FIG. 28 and particularly to both power spool 184 and signal spool 276 in their normally closed positions illustrated, one can trace the action of the safety relief valve upon a rise in pressure from pressurized bus duct 110. As pressure in the system rises, it is directed to the end 352 of signal spool 276. As this pressure rises above the selected setting of spring 266, the signal spool begins to move in the direction to compress the spring. It will be noted here that just prior to the pressure level at which the spool moves, the passage 296 is connected via chamber 350 to the annular spool passage 356 at the forward spool throttling land 211 which communicates with passage 294 and henceforth through passage opening 316, orifice 306, recess 372 and chamber 348 at the end of power spool 184. It will now be understood that there is a dual flow path for the pressurized fluid to chamber 384 at the end of power spool 184 to insure that the static pressure is the same at the starting point of the control action. Now, then, as signal spool 276 moves downward, responsive to pressure rise, the communication of chamber 350 to

passage 294 via annular flow passage 276 in the spool is closed, whereby it is made ineffective for subsequent operation. Also pressurized fluid exits in passage 314, having been reflected through orifices 328 and 302 from line 380, and is communicated through recess 360 and annular spool passage 362, to throttling land 213 which is shown in its normal closed position with respect to the recess port 364 and low pressure return line 252 leading to reservoir 74.

- 10 As signal spool 276 continues to move downwardly under the rise of pressure, throttling land 213 begins to open recess port 364 and pilot flow begins to flow via passage 162, passage opening 314, and this develops a pressure drop from passage 380 across orifice 302 and 15 328. This pressure drop is essentially reflected across the opposite ends of the power spool 184, one end 295 being essentially at line pressure and the other end 248 being essentially at a reduced pressure determined by the pressure which exists in line 314 as the flow develops across the control orifices mentioned. This pressure drop across the power flow spool 184 begins to move such spool against control spring 194. The passage 216 which has been at maximum pressure level is then communicated, by the action of throttling land 25 215 being opened, to recess port 208 as the power spool begins to further open and so power flow develops from bus duct 110 via passages 368 and 216, to recess passage 208 and passage 252, port 238, bus return duct 112 and henceforth to reservoir 74.
- 30 It will now be seen that action of the signal spool 276 is to pilot operate power spool 184 into a modulating open position responsive to pressure in pressurized bus duct 110. If the pressure tends to increase significantly, the multiple spool actions result in further opening of 35 power spool 184 such that the entire flow, if necessary, will be conducted into low pressure passage 252 and henceforth to reservoir at the operating pressure sensed by the signal spool 276. Therefore, complete release of flow from the system is accomplished and limiting of the pressure in the duct 110 is effected. Conversely, if pressure in bus duct 110 begins to fall below a preset value, as determined by the setting of signal spring 266, then the signal spool will begin to move toward its normally closed position in a modulating manner and the control flow developed across orifice 302 will be diminished and therefore the pressure drop applied to the power spool 184 will be lower and control spring 194 will return power spool 184 toward its closed position in a modulating manner. Flow will then be reduced from recess port 218 to recess port 208 across the throttling land 215 and the valve will begin to close and restore the system to its original state of pressure and flow.

- 55 A further reduction of the pressure, sensed by signal spring 266, will eventually open the throttling land 211 of the signal spool 276 such that chamber 350 is once again communicated with annular spool recess 354 and pressurized fluid is rapidly directed to the lower end of the power spool 184 via passage opening 316 and orifice 306 as was the case before the pressure rise occurred. This provides for a rapid equalization of pressure across the power spool whereby the springs can rapidly move the spool to its normally closed position.

- 60 Certain orifices are installed in the universal passage arrangement of the module housings, as shown in FIG. 28, for the purpose of damping and improving the response rate of the various elements. For example, ori-

fice 322 is shown for controlling the flow from the end 395 of the power spool 184 when it is returning to its normally closed position. Since flow discharging from the end 295 of the spool cannot return through check valve 226, biased by spring 230, such flow is forced to return through orifice 322 to the main pressurized line. This accomplishes a damping or slowing up of the return rate of the spool for purposes of stability in the power flow module. In a similar manner, orifice 318 communicating with chamber 350 at the end of signal spool 276 provides a damping or slowing up of fluid flow as it effects the operation of such spool.

Also, certain vibrations or pulsations occurring in the pressurized line are reduced or prevented by orifice 318 from acting directly on end 352 of signal spool 276. This provides stabilizing and tends to prevent chatter and unstable conditions during control operations. Similarly, orifice 306 provides for a high resistance to flow discharging from the end of power spool 184 when the power spool is required to open rapidly. The discharge flow through orifice 306 would normally be combined with the pressure flow across orifice 302 to act through the signal spool 276 at the throttling land 213 when it is in its opening position. If this flow were too high, the power spool 184 could open too rapidly and cause excessive oscillations, but orifice 308 limits the rate at which power spool 184 can open responsive to signal spool 276.

Orifice 306 is essentially a similar damping orifice which acts in conjunction with orifice 318 to control the rate at which fluid is allowed to proceed into the chamber 348 at the end of power spool 184. However, this does not affect the direct pulsation level at the end of signal spool 276 as was the case with orifice 318.

Orifice 328, FIG. 28, shown with a wire insert and called out at 4 in the code, FIG. 28-A, is provided with a larger orifice characteristic and the essential function of this arrangement is to provide a certain amount of filtering of particles due to the wire insert. It presents an annular orifice characteristic and is not so subject to being clogged by a single particle of contaminant. A round hole orifice or single hole orifice would have this sensitivity to a single foreign particle. It will now be seen that such orifice 328 provides a certain degree of single chip filtration to the other important control orifices in the arrangement.

As seen in FIGS. 13 and 28, the fluid chamber indicated at 188 represents an unusually large volume of hydraulic fluid provided at the end of power spool 184 which volume provides a capacitive or resilient effect on the spool during rapid pressure changing conditions.

As previously mentioned, when the throttling land 211 has been shut by the action of pressure on signal spool 276, there is a high resistance orifice arrangement in the path for pressurized flow from line 368 to recess 372 and chamber 348 on the end of the spool 184. Flow cannot arrive at recess 372 very rapidly, through such high resistance path, whereby the pressure acting on power spool 184 at the opposite end 295 tends to move the spool downwardly against capacitive chamber 188 thereby compressing the fluid therein. This action provides a more rapid movement of power spool 184 to the open position than would normally be possible without such resilient capacitive chamber 188. This occurs at rather relatively high frequency and is limited by orifices previously mentioned. The action that is obtained is to improve the quality of control

since it provides a rate of change sensing of system pressure and allows the spool to rapidly open.

Reference is next made to FIGS. 1 - 3, 21 - 26, 27 and 31 for the purposes of describing the operation of the pressure compensated flow control valve module 100 and reverse check valve module 434 combination which is generally shown on the strip chart of FIG. 3 at 100 and 434. This valve and check arrangement functions to control the flow to cylinder 106 from branch duct 138 of branch assembly 132. Reverse check valve module 434, FIGS. 26, 27 and 31, is interposed between side block 98 and pressure compensated flow control valve module 100 as seen in FIG. 1 and flow is directed from pressurized branch duct 138 to inlet port 474 of reverse check valve module 434 and proceeds to an inlet passage 244 of flow control valve module 100. Flow is blocked from proceeding through opening 45, FIGS. 27 and 31, by a check valve 102 and plug 454. Flow to port 220 is also directed to the top end of the spool 184 through line 376 and passage opening 320 and check valve 226 and pressure is thus directed to side 295 of power spool 184. The flow also proceeds through orifice 416 and opening 414 to sleeve recess 210 through annular passage 204, port 202 and line 242 and hence to port 478 which communicates with drain duct 140 of branch assembly 132 and therefore proceeds to the rod side of power cylinder 106 as seen in FIG. 3. Pressurized fluid is also delivered from the other side of orifice 416, FIG. 31, to passage 410 and opening 412 to end 348 of power spool 184. The pressure drop across orifice 416 then is reflected across power spool in a manner such that an increasing pressure drop tends to move the spool against the bias of control 194, which has been holding the spool in a normally open position connecting port 210 to port 202. Flow proceeding through orifice 416 and through power spool 184 is throttled at port 210 by the action of the pressure drop across orifice 416 against the combined spring forces of springs 194 and 230 acting to maintain the spool in a normally open position. If the flow varies for any reason, such as the occurrence of a pressure drop across the orifice, the spool acts to throttle the back pressure on orifice 416 to maintain a relatively constant flow across the orifice to provide a pressure compensating flow control device.

The check valve module 434, FIG. 31, is programmed with passages obstructed at plugs 454 and 456 to provide a return flow path from ports 478 to 474 when the flow is reversed. Therefore, when flow is directed from branch duct 140 leading from power cylinder 106 to port 178, it is directed through opening 458 and check valve 102 to supply fluid to line 474 with very light resistance being provided by spring 442 acting on check valve 102. Therefore on a reverse flow basis the flow is directed to by-pass the pressure compensated flow control valve 100, without being restricted by the action of said flow control valve.

With continued reference to FIG. 31, pressure compensated flow control valve 100 includes an orifice 322 that functions as a damping orifice for controlling the rate of movement of spool 184 for stability reasons.

It should be mentioned that the two valve modules of FIGS. 13 and 25, described above, are examples of different programming of the universal valve module and in the structures certain major valve elements are identical and standard so as to permit the selective programming of the different valve modules. The flowing

parts are the same: spool 184, sleeve 182, spring adapter 196, spring 194, spring housing 192, reset check valve 226, and reset spring 230, all of which represent the basic multiple function components of the universal power flow valve module that permit the programming of a wide variety of modulating and flow switching functions. The various orifices, springs, spacers and other standard valve components are utilized on a programmed basis to provide operation of the device for various selected valve functions. It should be pointed out that in the case of the pressure compensated flow control valve 100, FIGS. 25 and 31, the power spool 184 is shown shifted to a normally open position by the action of a spacer 406 so that port 210 is normally open to port 202 via annular spool passage 204 for normally open operation adapted to be pressure biased closed against the action of control springs 194 and 230.

As seen in FIGS. 14 and 25, spacer 406 has been installed so as to position spool 184 in a left position, as compared to its position of FIG. 15 thereby compressing spring 230. The spool 184 is, however, adapted for additional movement to the left with its guide portion 198 still retained in spring adapter 196. The function of control spring 194 is to bias spring adapter 196 against the right end of sleeve 182. If pressure is developed across power spool 184 in a direction to shift it to the right, then the spool transmits force to spacer 406 which in turn shifts spring adapter 196 to the right compressing control spring 194. Spacer 196 permits spool movement back to inner surface 201 in spring housing 192 before stopping the spool movement. Hence it will be seen that the structure just described provides for programming the power spool 184 for normally open operation merely by the installation of a simple spool spacer 406 with the continued provision of control pressure forces on the end of the spool to force it to close the proper porting by axial shifting movement in sleeve 182. The general arrangement is such that control spring 194 on the right end of the spool 184, FIG. 25, is stronger in force level than reset spring 230 on the left end of spool, said reset spring 230 transmitting force to spool 184 via spring adapter and spool stop 226. Pressure at the right end of the spool 184 will still compress reset spring 230 until the spool is stopped by the action of spring adapter 226 engaging an inner shoulder 97 on housing 180-A. Spool movement in the opposite direction is terminated when spring adapter 196 engages inner surface or shoulder 201 on spring housing 192. It will now be understood that spool 184 can be shifted in either direction by pressure forces applied at opposite ends of the spool, but the spool movement is terminated by the spring adapter 226 engaging valve housing 180-A or by spring adapter 196 engaging spring housing 192, and yet the flow is established in a selected manner at the beginning of the control function by the action of the two springs 194 and 230 and their respective spring adapters which means that one can establish a precise positioning of the normal location of the spool. The control springs acting on power spool 184 do not function in an uncontrolled manner, but are controlled by the above described elements that limit the spring effects on the spool movement and generally the effect of each control spring is confined to the respective spool end at which the spring is functioning with such spring effect being isolated from the opposite spool end when required.

Referring again to FIG. 25, an adjuster assembly indicated generally at 104 is provided for controlling an orifice 416 which is the basic flow control orifice previously described. By turning adjustment knob 256, axial movement is imparted to adjusting stem 209 which moves a spacer 432 rod extension 420, and orifice poppet 418 in such a manner as to vary an annular orifice area generally indicated at 416 to provide more or less flow as may be required. It will now be seen that a selected setting of adjuster assembly 104 will present a particularly orifice area for flow to be controlled, and the action of the pressure drop across orifice 416 on power spool 184 is such as to cause a pressure compensating action in a manner to maintain constant pressure drop across orifice 416 and maintain a relatively constant flow.

Referring again to FIG. 25, a spacer 400 is shown interposed between the outer end of control spring 194 and a shoulder 394 on spring housing 192 which spacer 400 provides additional precompression of spring 194 whereby it exerts a greater bias force on spool 184 which is merely for the purpose of raising the pressure drop required across orifice 416 and therefore across power spool 184. It will be understood that the programming of spacer 400 over control spring 194 establishes a higher pressure drop level at which valve module is operated and has its effects on the accuracy and capacity of the module. This is part of the general programming procedures that are obtainable with the above described control springs, spacer adapter, spool stop, spacer and orifices.

It should be mentioned that in programming of the safety relief valve 46, FIGS. 13 and 15, the spacer 400 was omitted permitting control spring 194 to directly engage the spring housing 192 at shoulder 394 which established a lower pressure level due to relatively low spring force exerted on spool 184 for the particular programming. This is established for reasons of accuracy and stability, since the operational requirements for a relief valve are different from those of a flow control valve.

Reference is next made to the counter-balance valve with reverse check valve indicated generally at 90 in FIGS. 1 and 3 and illustrated diagrammatically in FIG. 30. This valve combination 90 is made up of the basic power flow valve module 222, the signal flow valve module 228, and the reverse check valve module 434-A. The numeral 434-A indicates a different programming for the reverse check valve module as compared to the same basic 434 module previously described.

With reference to FIG. 30, the power flow valve module 222 operates essentially the same as previously described except that portion of safety relief valve 46, FIGS. 13 and 28, when the flow is being passed through the counter-balance valve 90 from port 474 to port 476 in a forward direction through the valve. Also, the signal flow valve module 228, including signal spool 276, operates the same as the signal flow valve module of the safety relief valve 46 previously described where the signal module across orifice 302 develops a pressure drop to move power spool 184 in the open direction permitting flow to occur from passage 474 to passage 376 leading to the pool end.

The reverse check valve module 434-A, FIG. 30, is combined with the power flow valve module 222 to provide a reverse check programming of operating in a reverse direction to be described.

In the forward direction of operation, just described, the check valve 94 is inoperative since a plug 450 is installed and no flow is permitted in the direction of inlet port 474. Now flow passing through power spool 184 is precisely the same as previously described with respect to the spool being controlled by the signal flow module 228. It will be noted from FIG. 30 that signal flow module 228 includes a passage 252 that communicates back to reservoir via drain port 476, side arm duct 142, branch duct 140 and bus duct 112, FIG. 3. Hence it will be seen that the ball check valve 94 is inoperative during the forward direction of operation of counter-balance valve 90.

In the reverse direction of operation of valve 90 where flow is coming into port 476 and trying to find its way to port 474, operation is different. The power spool 184 is in a normally closed position and the chamber at end 207 of signal spool 276 is communicated to pressure via passage 252 and hence the other end 352 will be at the pressure of port 474. Inlet pressure at port 476 holds signal spool 276 closed so that signal flow is not occurring at this stage of operation. The return flow from port 476 is delivered to sleeve recess port 208 at the power spool 184 and is obstructed by such spool being in a closed position. However, flow is also directed through unplugged passage portion 456 in check plate module 434-A and through the ball check 94 and unplugged passage portion 454 to passage 366 that communicates with chamber 348 at the end 295 of power spool 184. Flow to passage 376 is checked by the check valve 220 in chamber 348 and can only proceed through orifice 322 via passage 320, 376 and finally into housing recess 218, spool recess 216 and passage 368 which connect with the port 474 of the check valve module. This completes the reverse flow path for the signal flow. It should be mentioned that a very small signal flow is established since orifice 322 is programmed as a small orifice. Hence not much flow can develop through the check valve pilot flow path. However, the flow resistance to chamber 348 at the end of power spool 184, FIG. 30, is relatively low and a relatively high pressure develops in this chamber and on spool end 295 which biases power spool 184 in the direction to open port 208 to port 218 in the reverse direction for high flow. In this way the ball check 94 performs the function of directing signal flow into the orifice 322 to develop back pressure on power spool 184 to move it against control spring 194 to the full open position connecting ports 208 and 218 via annular spool recess 216. The essential advantage realized is that a small size check valve is arranged to operate the power spool in such a manner as to open it in a reverse direction using a small signal flow to accomplish a large reverse opening of the spool which would not normally be possible since the spool is in a normally closed position. Also this eliminates the necessity of the very large check valve arrangement for handling the full flow around the power spool elements. So in a sense power spool 184 is utilized as a reverse check valve of high capacity when it is operated from the small signal check 94 in the manner described. In all cases during the reverse flow of this counter-balance valve module 90, signal spool 276 has been maintained shut by providing back pressure at the spring end 207 of the spool whereby it performs no pilot action of counteracting the opening of the spool.

Furthermore the end 348 of power spool 184, which is biased by control spring 194, is connected during this reverse flow action via housing recess 372 to orifices 308, 302, 328, passages 380, 382 and open passage portion 326 to the port 218 so that the pressure drop across power spool 184 is in the reverse direction caused by the signal check 94. Hence there is a natural pressure drop across the port to open it in the direction to connect port 476 to 474 without any further operations within the valve.

Reference is next made to FIGS. 1, 3 20 and 32, for description of the cross relief valve modules 24 - 28. These valves are mounted in left branch assembly 130, FIGS. 1 and 3, for controlling the rotary fluid motor 108 and more particularly for relieving excessive pressure to the motor during stopping or reversing the direction of rotation of the motor. This description relates to both relief valve modules 24 and 28 both of which include the same universal spool and associated elements. These are mounted in a module housing 180-B which is essentially the same as housing 180-A used with the other valve modules previously described. Housing 180-B does not have signal passages on the top side for connection with a signal flow valve module and includes only a minor amount of interconnecting drillings required for basic valve functions. The present housing 180-B is essentially the same with respect to its size interfaces 99 and ports such that when it is being manufactured it can be fabricated from a standard universal body previously described with respect to relief valve 46 and the counter-balance valve 90. Hence it will be understood that the more complex signal passage arrangement need be provided only where the particular programming requires it. With continued reference to FIGS. 20 and 32, dome 186-A is modified as compared to dome 186 of the previously described valve modules in that a hole is provided in the top side for the mounting of a spring adjuster mechanism 38-40 and the standard spring housing 280 is mounted in such hole. The same previously described adjusting knob 256 and stem 209 are used here, but a new set of parts are used comprising spring adapter 490 utilized to mount the end of a heavy spring 492 which is mounted at its other end by a spring retainer 494 and a pivotal ball 496 which engages the standard adapter 196 engaging power spool 184 and performing the stop functions for the spool as previously described. The action of this standard interchangeable modular assembly on the standard power spool 184 is to bias the spool with a relatively heavy spring force so that direct pressure control can be utilized without the need for pilot operation of spool 184 where only low pressure requirements are present for operating, for example, a low pressure fluid motor 108. This essentially represents direct spring operation of the universal power flow valve module 222, rather than pilot operation by the signal flow valve module 228 previously described. This provides a more simple and economical programming for certain types of control of low pressure systems. It also is applicable to some control systems where higher degree of response or a more positive action is required since pilot operated valves inherently tend to be slower in response and more vulnerable to erratic operation under certain control conditions.

With reference to the cross relief valve generally indicated at 28 in FIGS. 1 and 3, one side of fluid motor 108 is connected to inlet port 244 of the cross relief

valve by branch duct 134 whereby pressurized fluid is available for driving the motor in one direction via sleeve recess 220. This flow is blocked by a plug 416 in passage 177 and is directed through unplugged passage portion 320 through check valve 226 to end 295 of power spool 184. This pressure then in the branch duct 134 is acting on spool 184 against the bias spring 492 which has been set by control adjuster 40. Spool 184 is normally closed before actuation so that passage 220 is not connected to passage 214 with port 240 blocked from port 238. Such normally closed programming of power spool 184 is established by omitting spool spacer 406, FIG. 14, which spacer was used in programming the flow control valve module 100 and omitted in programming the safety relief valve module 46 and the counter-balance module 90.

In operation of the cross relief valve 28, as pressure rises in branch passage 134 it is reflected via port 244 to the end 295 of power spool 184 which pressure opposes spring 492 and forces the spool to begin to move against the action of the spring 492. Subsequent rise in pressure beyond the selected setting of control adjuster 40 opens port 220 to port 214 via spool recess 216 thereby connecting passages 238 and 244. In effect, if the pressure at motor 108 is as high as the setting of the valve, flow in branch duct 134 is directed in a short circuit manner around the motor to branch duct 136 and pressure across the motor is thereby limited.

With reference to FIGS. 20 and 32, chamber 498 that houses spring 492 is maintained at the lower pressure of drain port 238 during operation by passage 410 and sleeve recess 214 which connect chamber 498 with said drain port 238. As a result the pressure at inlet port 244 is measured against the force of spring 492 without any back pressure in spring chamber 498. Having described how power spool 184 opens as the pressure rises, as the pressure falls at inlet port 244 connected to branch duct 134, the spool then returns to its normally closed position by the action of spring 492 opposing the pressure in line 244 and shuts off the flow from inlet port 244 to port drain 238.

In operating motor 108 the reverse direction, if higher pressure is present at port 238 and port 244 is at low pressure, power spool 184 being in the normally closed position acts as a complete block to flow and therefore no flow can occur.

The operation of the other cross relief valve 24, FIGS. 1 and 3, is the same as that of cross relief valve 28 but in the reverse direction. Therefore, branch duct 136 is at pressure set by the control adjuster 38 of cross relief valve 24 and flow is directed from branch duct 136 to the other branch duct 134 by the action of cross relief valve 24 in the same manner described previously for cross-relief valve 26 but in the opposite direction, and once again power spool 184 is in its normally closed position; therefore, the two cross relief valves oppose each other in parallel across the branch ducts 136 and 134, with one operating in one direction and the other operating in the other direction so that pressure relief of the bi-directional flow through fluid motor 108 is effectively realized by independent adjustments of the two valves.

In general, the cross relief valves 24 and 28 represent simplified pressure control valves and for purposes of economy and simplicity should be used under certain conditions. Also, it will now be understood that the universal power flow valve module can be changed in pro-

gram to effect various control functions depending upon the requirements including spring operation of power spool 184 and signal flow operations either by flow signals or pressure signals or by pressure signals resulting from flow changes or in any other manner required for a particular control operation.

With reference to FIGS. 20 and 14, a spacer 406 can be inserted over spool 184 to program the valve for normally open operation where the spool recess connects ports 214 and 202. A rise in pressure at port 244 will then cause normally open ports of 202 and 214 to be closed rather than opened as was the case when the valve of FIG. 20 is programmed for the cross relief operation as described above. When ports 220 and 214 are opened by a rise in pressure the spool spacer 406 effects a change in the programmed function of the spool similar to the change function described with respect to the pressure compensated flow control valve of FIGS. 21 - 24 and 31.

Reference is next made to FIGS. 1, 3 and 34, for purposes of describing a filter and relief valve module indicated generally at 62 and shown mounted on a series side block 58. This combined module 62 performs both a filtering and bypass relief function.

Referring particularly to FIG. 34 which is a schematic showing of the filter and relief valve module, an inlet port 566 connects with bus return duct 112, FIG. 3, and all return flow from the entire control system is directed into this passage. Flow passes into chamber 568, through filter element 179 where it is filtered of contaminates and then to inner chamber 570 from which it is released via passage 572 and line 580 to reservoir 74, FIG. 3. If for some reason filter element 179 becomes clogged which produces an extra high pressure drop from chamber 568 to chamber 570 in the direction of flow, then flow is directed from chamber 568 through a check valve 64 to passage 572 and henceforth to reservoir 74 via passage 580.

As seen in FIG. 34, check valve 64, biased closely by spring 578 in passage 574 connects to chamber 568 by passage 574 and the other side of the check valve connects to passage 572 via passage 576. Spring 578 maintains the check valve 64 in a closed position until a predetermined pressure is present across the check valve sufficient to permit flow from chamber 568 to passage 572.

Reference is next made to FIG. 33 which is a flow diagram of a direct spring operated four-way valve 32 of FIGS. 1 - 3. Valve 32 is mounted on branch assembly from which the flow from pressurized bus duct 110 and branch duct 134, FIG. 3, is directed through the blocks to the pressure input port of the four-way valve 32 at module port 172 which connects with the pressure inlet port 526 in the diagrammatic view of FIG. 33. The flow is then directed to a sleeve recess port 514 with spool 502 in a closed position so that the flow is blocked.

In operation of four-way valve 32, the flow conducted from bus duct 110 to the inlet port of the four-way valve is directed from inlet port 514 to either port 516 or port 512 depending on the direction spool 502 is shifted responsive to energization of solenoid actuators 498 or 500. If actuator 498 is energized, the spool is moved to open port 514 to port 512 and in FIG. 3 flow occurs between port 172 to 176 and into branch duct 136 to the fluid motor 108. Simultaneously as the port 514 is connected to port 512, port 516 is also con-

nected to 518 and therefore in FIG. 3 the flow from port 174 is direct to 178.

If the other solenoid actuator 500 is energized, spool 502 is shifted to connect ports 514 and 516 and also port 512 is connected to port 510. This conducts pressurized fluid to motor 108 via the other branch duct 134 to operate the motor in a reverse direction.

It will now be seen that the four-way valve directs flow to one port of the fluid motor while at the same time it drains the other port of the fluid motor to reservoir 74 via the drain ducts 136 and 112 in the conduit modules. Hence it will be understood that the solenoid action on the four-way spool directly operates the four-way valve control to accomplish a four-way directional switching of the flows to and from motor 108.

Referring to FIGS. 1, 3 and 29, the other four-way valve 82 mounted in branch assembly 132 serves as a flow-switching function for power cylinder 106. FIG. 29 diagrammatically illustrates a pilot operated four-way valve with a power section including a main spool 560 being shown at the left side of the diagram of FIG. 29. A signal section including a signal spool 502-A is shown at the right side of the diagram of FIG. 29 and such signal section is substantially the same as the direct spring four-way valve shown in FIG. 33.

In operation, the solenoid operated signal spool 502-A serves to operate a second stage four-way valve to provide directional flow control of the power flow. The pilot operated four-way of FIG. 29 is used instead of the direct spring four-way valve of FIG. 33 for higher flow conditions for the same reasons as the pilot operated modulating valves previously described. In these instances a solenoid operated signal spool in signal section controls a very small signal flow that is arranged to shift a larger power spool that controls the main power flow without the requirement for larger solenoids.

Referring particularly to operation of the pilot operated four-way valve 82 of FIG. 29, the pressurized bus duct 110 of FIG. 3 conducts pressurized fluid to the four-way valve via branch duct 138 in center block 80 and such fluid is directed to port 150, FIG. 3. Port 150 in turn connects to valve inlet port 534 seen in the diaphragmatic circuit of FIG. 29 and pressurized fluid is then delivered to housing recess port 548 closed by power spool 560 in its normally closed position. A branch path in the circuit of the pilot operated four-way valve is shown at line 582 which directs pressurized fluid to the signal section inlet port 526 so that pilot pressure is available at housing recess port 514 closed by signal spool 502-A as previously described. During normal operation, if solenoid 498 is actuated, pressurized fluid from inlet port 534 is delivered via line 582 and 514, the latter being connected to housing recess port 512 by the action of the solenoid 498 and the pressurized fluid is then conveyed via ports 528, 530 and 554 to end 558 of power spool 560. This shifts the power spool in a direction to connect pressurized port 548 to port 550 whereby fluid is released out through port 532. This delivers fluid between module ports 150 and 154 in the flow sheet of FIG. 3 and thence through counter-balance valve 88 via line 144 to power cylinder 106.

At the same time, main spool 560 was shifted to connect port 548 to 550, port 546 is also connected to port 544 which connects the opposite side of power cylinder 106, FIG. 3, from pressurized branch duct 138 to mod-

ule port 152 which connects to module port 156 and ducts 140 and 112 back to reservoir.

It should be mentioned that signal spool 502-A, FIG. 29, is arranged so that in its centered position ports 516 and 512 are vented to low pressure via ports 510 and 518 and ports 522 and 538 leading back to reservoir 74. In this way it differs from signal spool 502 of FIG. 33. This permits springs 556 and 564 to center the power spool. Hence the schematic diagram of FIG. 29 shows port 512 connected to port 510 and port 518 connected to port 520 when the spool is centered by the modified positions of the lands on the spool that are so arranged that they do not fully cover the sleeve recess ports 510 and 518. This provides for the pilot operation and spool return to center. It will be noted that in the case of the direct spring operated four-way valve of FIG. 33 the spool lands cover sleeve recess ports 510 and 518 such that the valve is closed center with the two ports 510 and 518 isolated from reservoir for operation of the fluid motor. Hence it will be seen that there is necessarily a slight difference in the land configuration of the spool 502-A of the signal section of FIG. 29, but it is otherwise identical in operation to spool of the direct spring four-way valve in FIG. 33. In one instance the spool 502-A operates a main power spool 560, which in turn controls fluid motor 108, whereas in the other instance the spool 502 directly controls fluid motor 108.

I claim:

1. A programmable standardized power flow valve module provided with a valve interface having standardized conduit porting configuration adapted for mounting on a manifold system, said power flow valve module comprising standardized valve elements selectively adaptable for three-way operation, two-way operation, normally open operation or normally closed operation, said valve interface being provided with central, right and left power flow ports of standardized size and location, and right and left signal flow ports of standardized size and location, said module including a cylindrical spool bore; a standardized multiple function three-way valve spool slideably mounted in said bore and including right and left spool ends, right and left sealing lands and a central modulating land, said right signal flow port communicating with said right spool end, and said left signal flow port communicating with said left spool end; means for selectively positioning said valve spool at various locations in said spool bore to effect various multiple valving functions; and means for selectively biasing said valve spool in accordance with said multiple valving functions.

2. A programmable standardized power flow valve module provided with a valve interface having standardized conduit porting configuration adapted for mounting on a manifold system, said power flow valve module comprising standardized valve elements selectively adaptable for three-way operation, two-way operation, normally open operation or normally closed operation, said valve interface being provided with central, right and left power flow ports of standardized size and location, said module including a cylindrical spool bore; a standardized multiple function three-way valve spool slideably mounted in said bore and including right and left spool ends, right and left sealing lands and a central modulating land, said central power flow port communicating with said spool at said central modulating land, said right power flow port communicating

with said spool on the right side of said central modulating land, said left power flow port communicating with said spool on the left side of said central modulating land, said right signal flow port communicating with said right spool end, and said left signal flow port communicating with said left spool end; means for selectively positioning said valve spool at various locations in said spool bore to effect various multiple valving functions; and means for selectively biasing said valve spool in accordance with said multiple valving functions.

3. A programmable standardized power flow valve module provided with a valve interface having standardized conduit porting configuration adapted for mounting on a manifold system, said power flow valve module comprising standardized valve elements selectively adaptable for three-way operation, two-way operation, normally open operation or normally closed operation, said module also being selectively actuatable by either low force level mechanical or hydraulic signals, said module being further characterized by a standardized multiple function three-way valve spool selectively adaptable for either normally open or normally closed operation; means for selectively positioning said valve spool at various locations in said spool bore to effect various multiple valving functions; and means for selectively biasing said valve spool in accordance with said multiple valving functions.

4. A programmable standardized power flow valve module provided with a valve interface having standardized conduit porting configuration adapted for mounting on a manifold system, said power flow valve module comprising standardized valve elements selectively adaptable for three-way operation, two-way operation, normally open operation or normally closed operation, said module being further characterized by said valve module including a valve housing; a sleeve element including a first end forming a first spring stop, a second end forming a second spring stop and a sleeve guide for a spring adapter guide; a multiple function three-way spool shiftably mounted in said sleeve and including a first end provided with a longitudinally extending guide for a spring adapter and removable spacer and a second end; a first spring adapter on said guide including a shoulder arrested in one direction by said first spring stop and in the other direction by said housing; a first control spring of greater force magnitude between said first spring adapter and said housing; a second spring adapter shiftably mounted in said sleeve guide and interposed between said second spool end and said housing, said second spring adapter including a shoulder arrested in one direction by said second spring stop and in the other direction by said housing; and a second control spring of lesser force magnitude between said second spring adapter and said housing.

5. The apparatus defined in claim 1 that includes a programmable sleeve in said module and a programmable spool mounted in said sleeve.

6. The apparatus defined in claim 1 wherein said valve includes a spacer and spring for effecting said selective programming of said valve module.

7. The apparatus defined in claim 1 wherein said valve module includes a valve housing provided with a plurality of orifices for the selective programming of said valve module.

8. The apparatus defined in claim 1 wherein said valve module includes a spool element provided with a spool recess having a jet force compensator surface.

9. A programmable standardized power flow valve module provided with a valve interface having standardized conduit porting configuration adapted for mounting on a manifold system, said power flow valve module comprising a standardized multiple function three-way power flow valve spool selectively adaptable for various power flow valve functions; and a signal flow valve module including a standardized multiple function signal flow valve spool provided with a signal flow throttling land and a signal flow spool end exposed to flow in said system for sensing characteristics of said flow.

10. The apparatus defined in claim 9 wherein said signal flow valve module functions to pilot operate said power flow valve module.

11. The apparatus defined in claim 9 wherein said signal flow spool valve includes a control adjuster for varying the bias on said signal flow spool valve.

12. The apparatus defined in claim 10 wherein said signal flow spool valve includes a control adjuster for varying the bias on said signal flow spool valve.

13. A programmable standardized power flow valve module provided with a valve interface having standardized conduit porting configuration adapted for mounting on a manifold system, said power flow valve module comprising a standardized multiple function three-way power flow valve spool selectively adaptable for various power flow valve functions; and a signal flow valve module including a standardized multiple function signal flow valve spool provided with a signal flow throttling land and a signal flow spool end exposed to flow in said system for sensing characteristics of said flow.

14. The apparatus defined in claim 1 wherein said means for selectively positioning said valve spool comprises a longitudinally extending guide on one of said spool ends, and a removable spacer and spring adapter on said longitudinally extending guide.

15. The apparatus defined in claim 1 wherein said means for selectively positioning said valve spool comprises a longitudinally extending guide on one of said spool ends, and a removable spacer and spring adapter on said longitudinally extending guide; and wherein said means for selectively biasing said valve spool comprises a removable control spring in engagement with said spring adapter.

16. The apparatus defined in claim 9 wherein said power flow valve spool comprises a longitudinally extending guide on an end thereof, and a removable spacer and spring adapter on said spring guide for selectively positioning said power flow valve spool at a plurality of locations to effect said various power flow valve functions.

17. The apparatus defined in claim 9 wherein said power flow valve spool comprises a longitudinally extending guide on an end thereof, and a removable spacer and spring adapter on said spring guide for selectively positioning said power flow valve spool at a plurality of locations to effect said various power flow valve functions; and removable control spring means in engagement with said spring adapter for selectively biasing said power flow valve spool in accordance with said various power flow valve functions.

UNITED STATES PATENT OFFICE
CERTIFICATE OF CORRECTION

Patent No. 3,817,269 Dated June 18, 1974

Inventor(s) Robert E. Raymond

It is certified that error appears in the above-identified patent and that said Letters Patent are hereby corrected as shown below:

IN THE CLAIMS

Column 24, line 36, in Claim 13, after "flow" and prior to the " ." add the following clause -- , said signal flow valve module further including a standard signal flow valve interface provided with standard porting that registers with standard porting on an interface of said power flow valve module --

Signed and sealed this 1st day of July 1975.
